UNITED STATES PATENT OFFICE.

LEWIS W. HAGEY, OF ST. LOUIS, MISSOURI.

HEATING-STOVE.

SPECIFICATION forming part of Letters Patent No. 409,086, dated August 13, 1889.

Application filed March 5, 1888. Serial No. 266,152. (No model.)

To all whom it may concern:

Be it known that I, LEWIS W. HAGEY, of the city of St. Louis, in the State of Missouri, have invented a certain new and useful Improvement in Heating-Stoves, of which the following is a full, clear, and exact description, reference being had to the accompanying drawings, forming part of this specification, and in which—

Figure I is a front view of a horizontal stove, showing the projecting horizontal damper, with part broken away to show the lining and its bevel coping that prevents the entrance of ashes within the intermediate dead-air chamber. Fig. II is a vertical section of the stove, taken on line II II, Fig. I, and shows the interior of the stove, its lining, and dead-air chamber, with its projecting horizontal damper in profile. Fig. III is an enlarged vertical section of the projecting horizontal damper, taken on line III IV, Fig. II, showing the damper open; and Fig. IV is a like view showing the damper closed.

This invention relates to a horizontal heating-stove provided with devices for the economy of fuel, and having a draft adjustment comprising a projected horizontal damper that is located at the front end of the stove contiguous to the bottom thereof beyond the adverse influence of the falling ashes; and the invention consists in features of novelty, hereinafter fully described, and pointed out in the claims.

Referring to the drawings, in which like figures of reference indicate similar parts in all the views, 1 represents the horizontal body of one of my heating-stoves. The bottom 2 of said stove is preferably made of cast-iron, but may be, like the sides 3, ends 3^a, and top 4, made of Russia iron or any other suitable sheet metal.

The interior of the stove is provided with a sheet-metal lining 5, which may ascend from the bottom two-thirds up the side of the stove, more or less, and which may be either of Russia iron or other suitable metal. This lining is placed parallel to and at a suitable distance from the outer casing to provide a dead-air chamber 6 in the intermediate space. The lining terminates at top in a bevel coping 7, the upper edge of which is attached to

the outer casing of the stove, thereby preventing the entrance into the dead-air chamber of ashes or cinders, &c., from the interior of the stove.

55

8 represents the projecting horizontal damper, which is constructed of an inner cylinder 9, that passes clear through the casing, dead-air chamber, and lining, near the bottom of the front end of the stove, and is held in its seat by its inner flanged periphery 9^a, that engages with the lining against which it fits. The said inner cylinder is terminated externally by a disk 10, that both forms a cap that closes in the end of the cylinder, and extending past said cylinder provides a peripheral flange 11, which holds to its seat the outer rotary cylinder 12, which fits snugly and rotates around the inner cylinder. In the construction of the outer cylinder the ends of the sheet metal where they meet at their circumferential junction are flanged outwardly and riveted together, as shown in Figs. III and IV, and beneath the damper in Figs. I and II, so as to form a handle 13 for the movement of the operative damper around the inner cylinder.

75

A U-shaped opening 14 is cut in the upper part of the inner cylinder, and a like aperture 15 is cut in the outer cylinder at the farther side from the handle 13.

80

It is evident that when the outer cylinder is in the position shown in Figs. I, II, and III, with its handle down, the U-shaped apertures of both cylinders are in corresponding position, and consequently the outer cylinder is fully opened and lets in a free full draft. On the contrary, when the outer cylinder is in the position shown in Fig. IV, with the handle elevated to its full capacity, the draft will be entirely shut off, for the close semi-periphery of the rotary outer cylinder then covers the aperture in the inner cylinder. When, again, it is desired to partially close the damper, the rotary outer cylinder of said damper is turned accordingly into an intermediate position.

85

It will be seen that by my device of a double cylindric damper projected horizontally entirely beyond the end of the base of the stove in conjunction with the position of the draft-opening thereto, and means of operating the

90

95

draft, means are provided for avoiding the choking of said damper by falling ashes from the fire, so as to always have when required a good and sufficient draft, and when it is desired to stop or nearly stop the combustion of the fuel the right adjustment of the telescopic double cylinder efficiently answers the purpose.

So as always to have more full control of the draft, no door is provided at the sides or ends of the stove, and consequently the draft can be shut off more effectually than it could be from any stove that was furnished with a side or end door and consequent feed-opening. The stove, having no door at the side or end, is provided with a feed-opening 16 in the top which, except when feeding, is closed by the cover 17.

Large blocks of wood and knots can be easily inserted through this opening in the top of the stove that it would be very difficult to insert through the usual feed-door, for the gravity of the feed assists its insertion from the top, but is obstructive to its passage through the usual doorway.

A small sliding damper 18 is inserted near the top in the front end of the stove. This damper usually remains closed, and is not intended, in the general way, to provide inspiration to aid combustion; but when the projecting cylinder-damper is closed at night, or at any other time, and in consequence the rarefied air in the stove expands faster than it finds vent through the flue 19, the upper sliding damper is opened to allow respiration to relieve the expansion. Sometimes, also, it may be desired to open the other damper to furnish an upper draft that will not undermine the fuel and too rapidly enforce combustion.

Among other advantages in this stove is its economic use of the fuel, through the peculiar arrangement of the cylindric damper,

and its easy adjustment relatively to a full, partial, or closed draft and its otherwise 45 closed front, as it has no feed-door. These stoves now in use, when the cylindric projected damper is closed, have kept fire for forty-eight hours, so that when opened it freely burns again, saving the trouble of re-laying the fire and saving the use of kindling. They will probably keep fire for a much longer period, if tried.

Another advantage of the free adjustment and peculiar arrangement of the draft is 55 that the heat can be arrested from escape through the smoke-flues, for it is nearly wholly economized within the stove for radiation within the apartment to be heated, in consequence of the above-described devices. 60

I claim as my invention—

1. In a heating-stove, the horizontal cylindric damper that projects in front of the stove near the bottom thereof, the outer cylinder having rotary movement around the inner 65 one, and both cylinders being provided with U-shaped openings that are adjustable to regulate the draft, the outer casing, and lining to the stove that supports the damper, substantially as and for the purpose set forth. 7c

2. The combination of the stove-body 1, lining 5, and projecting horizontal damper located near the bottom of the stove, consisting of the inner cylinder 9, formed with inner peripheral flange 9^a secured to the lining, the 75 U-shaped opening, and cap 10, having outer peripheral flange 11 and outer rotating cylinder 12, fitting around the inner cylinder, and formed with flanged handle 13 and U-shaped opening, substantially as described and 80 shown.

LEWIS W. HAGEY.
